UNITED STATES PATENT OFFICE

2,575,880

RECLINING ARTICLE OF FURNITURE

Anton Lorenz, Buffalo, N. Y.

Application January 21, 1947, Serial No. 723,413
In Sweden February 4, 1946

15 Claims. (Cl. 155—105)

1

This is a continuation-in-part of abandoned patent application Ser. #640,263 filed Jan. 10, 1946 for "A Reclining Article of Furniture," the latter being a continuation-in-part of patent application Ser. #580,377 filed March 1, 1945 for "A Reclining Article of Furniture" which matured into U. S. Patent 2,433,521.

The present invention relates to articles of furniture, and more particularly to a reclining article of furniture, wherein the seat and the back-rest form movable links of a polygonal compound linkage swingably mounted on a support, a portion of the latter forming the stationary link of said linkage.

An object of the present invention is to provide an article of furniture of above described type with a mechanism, simple in construction, for controlling the movements of the seat and the back-rest in dependence on each other.

A further object of the present invention is to provide a reclining article of furniture wherein the change in the angle between the back-rest and the seat during a movement of said members may be readily adapted to the requirements of users of the article of furniture.

Another object of the present invention is to provide a reclining article of furniture of above described type with means, by which the user of the article of furniture may alter the inclination of the back-rest while the seat is held in a predetermined position.

A further object of the present invention is to provide a reclining article of furniture of above described type with means, by which the user of the furniture may alter the inclination of the seat while the back-rest is held in a predetermined position.

Still another object of the present invention is to provide a reclining article of furniture of above described type with means, by which the user of the article of furniture may alter the degree of change in the inclination of the back-rest from the sitting position into the extreme reclining position while the degree of the change in the inclination of the seat from the sitting position into the extreme reclining position remains substantially unchanged.

A further object of the present invention is to provide a reclining article of furniture of above described type with means, by which the user of the article of furniture may alter the degree of change in the inclination of the seat from the sitting position into the extreme reclining position while the degree of the change in the inclination of the back-rest from the sitting position

2

into the extreme reclining position remains substantially unchanged.

Still another object of the present invention is to improve upon reclining articles of furniture as now ordinarily made.

With the above and other objects of the invention in view, the invention consists in the novel construction arrangement and combination of various devices, elements and parts, as set forth in the claims hereof, certain embodiments of the same being described in the specification and being illustrated in the accompanying drawings forming part of this specification, wherein:

Fig. 1 is a side elevational view of an adjustable desk chair according to the invention,

Fig. 2 is a sectional view of the desk chair shown in Fig. 1, taken on line 2—2, a portion of the seat being broken away,

Fig. 3 is a side elevational view of an adjustable reclining chair equipped with a movable leg-rest, a portion of a side wall of the support being broken away,

Fig. 4 is a sectional view of a locking device arranged on the chair shown in Fig. 3 taken on line 4—4 of Fig. 3 in an enlarged scale,

Fig. 5 is a side elevational view of another embodiment of an adjustable reclining chair according to the invention,

Fig. 6 is a side elevational view of still another embodiment of a reclining chair according to the invention, a portion of a side wall of the support being broken away,

Fig. 7 is a side elevational view of another embodiment of a reclining chair according to the invention, a portion of a side wall of the support being broken away,

Fig. 8 is a perspective view of the support of the chair shown in Fig. 7, a unit pertaining to the link-system of the chair being mounted in the support,

Fig. 9 is a fragmentary side elevational view of the safety device arranged on the support for holding the unit of the chair shown in Figs. 7 and 8 in its position,

Fig. 10 is a perspective view of a different embodiment of a unit, which may be used in the chair shown in Fig. 7, and

Fig. 11 is a sectional view of the locking device of the chair shown in Fig. 1, taken on line 11—11 of Fig. 1.

Referring now to Figs. 1 and 2, 10 generally indicates a pedestal of a desk chair, which may be of any conventional type. A supporting member 12 comprising a cross bar 14 and an extension 16 having an arm 18 on each side of the chair

is carried by a spindle 20 screwed into a threaded bore of the pedestal 10.

As best shown in Fig. 1, the rear end portion of a seat 38 is pivoted to the support 12 at 25. On each side of the chair, the lower end portion of a front link 40 is pivoted to said seat at 42. The upper end portion of said front link is pivotally connected at 44 with a connecting link 26. The lower end portion of said connecting link 26 is pivoted to the support 12 at 28 at a point spaced from the pivotal connection 25 between the seat 38 and the support 12. Said seat 38, said front link 40, said connecting link 26 and the stationary portion of the support 12 between the pivotal connection 28 of the connecting link 26 with the support and the pivotal connection 25 of the seat 38 with the support 12 form the links of a four-bar link-mechanism.

The lower end of a back-rest 22 is pivoted to the support 12 at 24 at a point spaced from the pivotal connection 25 between the seat 38 and the support 12. On each side of the chair, the rear end of a top link 30 is pivoted to an intermediate point 32 of said back-rest 22 above the pivotal connection 24 between the back-rest 22 and the support 12. The front end of each top link 30 is pivotally connected at 34 with an extension 96 of the connecting link 26. According to the drawings, said extension 96 of the connecting link 26 projecting beyond the pivotal connection 44 of the connecting link 26 with the front link 40 is integral with said connecting link; it is understood, that said extension 96 and said connecting link 26 could be made of two separate pieces rigidly connected with each other, if desired.

As will be apparent from above, the seat 38 and the back-rest 22 form movable links of a polygonal compound linkage comprising the movable links 38, 40, 26-96, 30, 22 and the stationary portions 28-25, 25-24 of the support 12.

When the user of the chair leans the weight of his body against the back-rest 22 so as to bring same into the reclined position shown in dash and dot lines in Fig. 1, the seat 38 is lifted through the medium of the front link 40 pivotally connected with the connecting link 26 which, in turn, is pivotally connected with the top link 30 pivoted to the back-rest in the manner described above. During said movement of the movable members of the chair from the sitting position shown in full lines into the reclined position shown in dash and dot lines, the angle between the back-rest 22 and the seat 38 is increased.

As will be readily understood, the degree of lifting the seat 38 depends on the length of the front link 40 and its connections with the connecting link 26 and the seat 38. For example, if the front link 40 were of shorter length and were connected with the connecting link 26 at a point below the pivot 44, the seat 38 would be lifted to a greater degree, when the proportions of the linkage 26-96, 30, 22, 24-25, 25-28 remain unchanged and the back-rest 22 is brought into the extreme reclined position shown in Fig. 1. In other words, owing to above described control of the seat 38 by the front link 40 pivoted to the connecting link 26, the designer of the chair has a wide range for obtaining different degrees of inclination of the seat and for obtaining different relative positions between the seat and back-rest in the reclined position, so as to make the chair as comfortable as possible for various uses. Furthermore, it may be mentioned, that the ar-

rangement of the movable members of the chair as described permits a construction of the chair with very well balanced movable members, which may be easily brought from one position into another one.

According to the embodiment shown in Fig. 1, the sitting position of the movable members of the chair is limited by a stop 46 arranged on the support 12 for cooperation with the seat 38. The extreme reclined position of the movable members of the chair is limited by another stop 48 mounted on the support 12 for cooperation with the back-rest 22.

The back-rest and the seat may be held in any desired position, for example in the extreme reclined position or in any other intermediate position, by means of a locking device generally indicated by 50 and arranged on a pivot 32 connecting the rear end of a top link 30 with the back-rest 22. As best shown in Figs. 1 and 11, said locking device 50 comprises a handle 51 screwed on the threaded end of the pivot 32. Said pivot 32 has a head 53 resting against the surface of the back-rest 22. A square portion 55 of the pivot 32 is inserted into a corresponding square aperture of the back-rest 22, whereby the pivot 32 is prevented from rotation when the locking lever 51 is turned. When the user of the chair loosens the locking handle 51, the surface of the hub 57 of said handle is disengaged from the surface of the top link 30, so that the movable members of the chair may be freely moved from one position into another one. When the locking handle 51 is tightened, the surface of the hub of the handle is pressed against the top link 30, whereby the latter is pressed against the back-rest 22 engaged with the head 53 of the pivot 32, so that the members of the chair are held in their position. Of course, any other type of locking device may be used instead of said locking device 50, if desired.

In the adjustable reclining chair shown in Fig. 3, the rear end portion of the seat 338 is swingably mounted on a casing-like support 312 at 325. Said seat 338 has a series of holes 356 near its front end. Likewise, the lower end portion of the front link 340 is provided with a series of holes 358, so that a pivot 342 may be selectively engaged with one hole of the series of holes 356 and one hole of the series of holes 358 for a pivotal connection of the lower end portion of the front link 340 with the seat 338. In a similar manner the connecting link 326 and its extension 396 are provided with a series of holes 360 for a selective engagement with a pivot 344 passing through a bore of the upper end of the front link 340. The lower end of the connecting link 326 is swingably mounted on the support 312 at 328 at a point spaced from the pivotal connection 325 between the seat 338 and the support 312.

The back-rest 322 is swingably mounted on the support 312 at 324 at a point spaced from the pivotal connection 325 between the seat 338 and the support 312. The rear end of the top link 330 is pivoted to an intermediate point 332 of the back-rest in a plane above the plane of the seat 338. The front portion of the top link 330 is provided with a series of holes 354 for selective engagement with a pin 334 passing through a bore of the extension 396 of the connecting link 326.

As will be readily understood, above described arrangement of the members of the polygonal compound linkage of the chair shown in Fig. 3

corresponds to the arrangement of the members of the polygonal compound linkage of the chair shown in Fig. 1. The arrangement of the various series of holes for selective engagement with various pins permits a modification and adjustment of the effective length of the connecting link 326 and/or front link 340 and/or top link 330 and/or seat 338.

A leg-rest 362 provided with a series of holes 364 is swingably mounted on the front end of the seat 338 at 366. One end of a controlling link 368 passing through a slot 379 of the support 312 is pivoted to the leg-rest 362 by a pin 370 passing through one hole of a series of holes 372 arranged on the controlling link 368 and inserted into one hole of the series of holes 364 of the leg-rest 362. The other end of said controlling link 368 is pivotally connected with a downward extension 352 of the back-rest 322 by means of a pivot 374 passing through one hole of a series of holes 376 arranged on the controlling link 368 and inserted into one hole of a series of holes 378 arranged on the downward extension 352 of the back-rest. According to the embodiment shown in Fig. 3, the downward extension 352 of the back-rest 322 projecting beyond its pivotal connection 324 with the support is integral with said back-rest 322; if desired, the back-rest 322 and the downward extension 352 of the latter could be made of separate pieces rigidly connected with each other. The effective length of the controlling link 368 may be varied and adjusted by the insertion of the pin 370 and/or the pin 374 into different holes of the various series of holes.

When the movable members of the chair are connected with each other as shown in Fig. 3, a movement of the back-rest 322 from the sitting position shown in full lines into the reclined position shown in dash and dot lines causes a movement of the seat 338 from the sitting position shown in full lines into the reclined position shown in dash and dot lines according to the same principle as described above in connection with Fig. 1. Furthermore, the leg-rest 362 is brought from the sitting position shown in full lines into the reclined position shown in dash and dot lines by means of the controlling link 368.

The sitting position of the movable members of the chair is limited by the upper edge of the support 312, on which the seat 338 comes to a rest, and the extreme reclined position of the movable members of the chair is limited by a stop 348 mounted on the support 312 for engagement with the back-rest 322.

Fig. 3 illustrates two locking devices. The first locking device 350 arranged on the pivot 332 is of the same construction as the locking device 50 described above in connection with Figs. 1 and 11. The second locking device generally indicated by 380 comprises a bar 382 swingably mounted on a frame member of the seat 338 at 384 as shown in Figs. 3 and 4. Said bar 382 has a slot 386 for slidable engagement with a bolt 388 having a square portion 390 inserted into a corresponding square aperture of the support 312. The bolt 388 has on one of its ends a head 392 for engagement with a surface of the bar. A locking knob 394 is screwed onto the opposite threaded end of the bolt 388 projecting from the support 312. If the locking knob 394 is loosened, the bar 382 may be freely moved, so that the seat 338 and the other movable members of the chair connected with the seat may be brought into any

desired position. If, however, the locking knob 394 is tightened, so that it clamps the bar 382 by means of the head 392 of the bolt 388 against the support 312, the seat and the movable members of the chair connected therewith are firmly held in their position.

If the members of the chair are connected with each other as shown in Fig. 3, the members may be held in any desired position by tightening 10 either one of said two locking devices 350 or 380.

If the user of the chair wishes to have the back-rest at a different angle relative to the seat when the latter is in a certain position, he may hold the seat in said certain position by tightening 15 the locking device 380. The other locking device 350 remains in loose condition. Now, the user of the chair may change the position of the pivotal connection 324 between the top link 330 and the extension 396 of the guiding link 326 by inserting the pin 334 into another hole of the series of holes 354, whereby the angle between the back-rest 322 and the seat 338 may be changed. Furthermore, the user of the chair may insert the pin 334 into another hole of the series of holes 360 of the guiding link 326 for changing the effective length thereof.

When the user of the chair wishes to have the seat in a different position relative to the back-rest when the latter is in a certain reclined position, 30 the back-rest is held in said position by a tightening of the locking device 350 while the locking device 380 remains in loose condition. Now, the user of the chair may bring the seat into a different position relative to the back-rest by altering the position of the pivotal connection 342 and/or 344 by inserting the respective pins into another hole of the series of holes 356, 358 and/or 360.

Above described change in the position of the back-rest 322 and/or the seat 338 causes a 40 change in the degree of change of angularity between the back-rest and the seat during a movement from the sitting position into the reclined position. If the back-rest alone is adjusted in a different position, the degree of change of the 45 inclination of the seat will remain substantially unchanged. If the seat alone is adjusted in a different position, the degree of change of the inclination of the back-rest will remain substantially unchanged.

In a similar manner, a change of the position 50 of the pivotal connections 370 and/or 374 by inserting the pins in different holes results in a change in the movement of the leg-rest 362 relative to the seat 338.

According to the embodiment of a chair shown 55 in Fig. 5, the support 512 comprises two side bars 511, 513 of tubular material, one on each side of the chair, which are connected with each other by a bracing member 515 and are mounted on a base member 517 of an integral piece of tubular material by welding, for example. The rear end of the seat 538 is swingably mounted on the support 512 at 525. On each side of the chair the lower end portion of a front link 540 is pivoted 60 to the seat 538 at 542. The upper end portion of said front link 540 is pivoted at 544 to the upper end of a connecting link 526, the lower end of which is pivoted to the support 512 at 528 at a point spaced from the pivotal connection 525 between the support 512 and the seat 538. The seat 538, the front link 540, the connecting link 526 and the stationary portion of the support 512 between the pivots 528 and 525 form a four-bar 65 link-mechanism.

The back-rest 522 is swingably mounted at 524 on the support 512 at a point spaced from the pivotal connection 525 between the seat 538 and the support 512. On each side of the chair the rear end portion of a top link 530 is pivoted to an intermediate point 532 of the back-rest 522 in a plane above the plane of the seat 538. The front end of the top link 530 is pivoted at 534 to an intermediate point of the connecting link 526 between the pivotal connection 544 of the connecting link 526 with the front link 540 and the pivotal connection 528 of the connecting link 526 with the support 521.

The sitting position of the movable members of the chair is limited by a stop 546 mounted on the support 512 for cooperation with the seat 538. When the back-rest 522 is swung about its pivot 524 into the extreme reclined position limited by an abutment of the back-rest 522 against the stop 548 mounted on the support 512, the movable members of the chair are likewise brought into a reclined position as shown in dash and dot lines in Fig. 5.

The movable members of the chair may be held in any desired position by means of a locking device 550 arranged on the pivot 532.

The mechanism of the chair shown in Fig. 6 substantially corresponds to the mechanism of the chair shown in Fig. 5. In Fig. 6, 638 indicates the seat pivoted to the support 612 at 625. 640 indicates the front link pivoted to the seat 638 at 642 and pivoted to the upper end of the connecting link 626 at 644. The lower end of the connecting link 626 is swingably mounted on the support 612 at 628. 622 indicates the back-rest swingably mounted on the support 612 at 624. 630 indicates the top link, one end of which is pivoted to the back-rest 622 at 632, the other end of which is pivoted to an intermediate point of the connecting link 626 at 634. In contrast to the showing of Fig. 5, however, the connecting link 626 is in the shape of a bent link, so that the three pivots 628, 634, 644 are not in alignment with each other. Thus, Fig. 6 illustrates a further modification of the mechanism according to the invention by the use of a bent link 626, whereby a further variation in the degree of the change of the angle between the back-rest and the seat during a movement thereof from the sitting position into the reclined position is rendered possible.

The sitting position of the seat 638 is limited by the upper edge of the front wall of the support 612. When the back-rest 622 is swung about its pivot 624 from the sitting position shown in full lines into the extreme reclined position shown in dash and dot lines and limited by the stop 648, the seat 638 is brought into its extreme reclined position, likewise shown in dash and dot lines.

According to the embodiment of a reclining chair shown in Figs. 7-9, the rear end of the seat 738 is swingably mounted on the support 712 at 725. On each side of the chair, the lower end of a connecting link 726 is rigidly connected with a transverse rod 728 rotatably arranged in recesses 729 of the side walls of the casing-like support 712. Said recesses 729 are open at the top. The two connecting links 726 positively connected with said transverse rod 728 form a unit generally indicated by 731 and swingably mounted in said recesses 729 of the support 712. During the assembling of the elements of the chair, said unit 731 may be readily inserted into said recesses 729 from above. The unit 731

is held in its position by means of safety members 733 attached to each side wall of the support 712 by screws. Furthermore, on each side of the chair, the upper end of a telescopic front link 740 is pivoted to the upper portion of the unit 731 at 744, and the lower end of each telescopic front link 740 is pivoted to the seat 738 at 742. The effective length of each telescopic controlling link 740 may be adjusted by means of a set screw 741. Each connecting link 726 of the unit 731 has an extension 796 projecting beyond the pivotal connection 744 between the front link 740 and the unit 731. The back-rest 722 is swingably mounted on the support 712 at 724. On each side of the chair, the rear end of a top connecting link 730 is pivoted to an intermediate point 732 of the back-rest 722. The front end of each top link 730 is pivoted to an extension 796 of the unit 731 at 734.

The back-rest 722 has a downward extension 752 substantially in the center of the chair. One end of a telescopic controlling link 768 is pivoted to said extension 752 at 774, the other end of said telescopic controlling link 768 passing through a slot 779 of the support 712 is pivoted at 770 to a leg-rest 762 swingably mounted on the seat 738 at 766. The effective length of the telescopic controlling link 768 may be adjusted by means of a set screw 769.

The sitting position of the movable members of the chair is limited by the upper edge of the support 712 cooperating with the seat, and the extreme reclined position of the movable members shown in dash and dot lines is limited by a stop 748 mounted on the support for cooperation with the back-rest.

The movable members of the chair may be held in any desired position by means of a locking device 750.

Fig. 10 illustrates a different embodiment of a unit 731a which may be substituted for the unit 731 of the chair shown in Figs. 7 and 8. According to Fig. 10, the unit 731a is made of an integral rod shaped in suitable manner.

I have described preferred embodiments of my invention, but it is understood that this disclosure is for the purpose of illustration, that the invention may also be applied to various other types of reclining articles of furniture, such as garden chairs, chairs for use in railroad cars, chairs for use in airplanes, sofas, lounges, etc., and that various omissions or changes in shape, proportion and arrangement of parts, as well as the substitution of equivalent elements for those, herein shown and described, may be made without departing from the spirit and scope of the invention as set forth in the appended claims.

What I claim is:

1. A reclining article of furniture, comprising:
60 a support, a seat pivoted to said support at its rear end portion, a connecting link, the lower portion of said connecting link being pivoted to said support at a point spaced from the pivotal connection between the seat and the support, a front link, the lower portion of said front link being pivoted to the front portion of said seat, the upper end portion of said front link being pivoted to the upper portion of said connecting link, said seat, said front link, said connecting link
65 and the stationary portion of the support between the pivotal connections of the connecting link with the support and of the seat with the support forming the links of a four-bar link-mechanism, a back-rest, said back-rest being pivoted to said support at a point spaced from and

front link, the lower portion of said front link being pivoted to the front portion of said seat, the upper end portion of said front link being pivoted to the upper portion of said connecting link, said seat, said front link, said connecting link and the stationary portion of the support between the pivotal connections of the connecting link with the support and of the seat with the support forming the links of a four-bar link-mechanism, a back-rest, said back-rest being pivoted to said support at a point spaced from and out of coaxial alignment with the pivotal connection of the seat with the support, a top link, the rear end of said top link being pivoted to an intermediate point of said back-rest above the pivotal connection between the back-rest and the support, the front portion of said top link being pivoted to a point of the connecting link spaced from its pivotal connection with the front link, and means whereby the effective length of said top link may be varied and adjusted.

8. A reclining article of furniture, comprising: a support, a seat pivoted to said support at its rear end portion, a connecting link, the lower portion of said connecting link being pivoted to said support at a point spaced from the pivotal connection between the seat and the support, a front link, the lower portion of said front link being pivoted to the front portion of said seat, the upper end portion of said front link being pivoted to the upper portion of said connecting link, said seat, said front link, said connecting link and the stationary portion of the support between the pivotal connections of the connecting link with the support and of the seat with the support forming the links of a four-bar link-mechanism, a back-rest, said back-rest being pivoted to said support at a point spaced from and out of coaxial alignment with the pivotal connection of the seat with the support, a top link, the rear end of said top link being pivoted to an intermediate point of said back-rest above the pivotal connection between the back-rest and the support, the front portion of said top link being pivoted to a point of the connecting link spaced from its pivotal connection with the front link, and means whereby the effective length of said seat may be varied and adjusted.

9. A reclining article of furniture, comprising: a support, a seat pivoted to said support at its rear end portion, a connecting link, the lower portion of said connecting link being pivoted to said support at a point spaced from the pivotal connection between the seat and the support, a front link, the lower portion of said front link being pivoted to the front portion of said seat, the upper end portion of said front link being pivoted to the upper portion of said connecting link, said seat, said front link, said connecting link and the stationary portion of the support between the pivotal connections of the connecting link with the support and of the seat with the support forming the links of a four-bar link-mechanism, a back-rest, said back-rest being pivoted to said support at a point spaced from and out of coaxial alignment with the pivotal connection of the seat with the support, a top link, the rear end of said top link being pivoted to an intermediate point of said back-rest above the pivotal connection between the back-rest and the support, the front portion of said top link being pivoted to a point of the connecting link spaced from its pivotal connection with the front link, and locking means as-

sociated with at least two members of the article, at least one of said members being a member of the linkage including said connecting link, said top link and said back-rest for locking said linkage with the back-rest in a predetermined position.

10. A reclining article of furniture, comprising: a support, a seat pivoted to said support at its rear end portion, a connecting link, the lower portion of said connecting link being pivoted to said support at a point spaced from the pivotal connection between the seat and the support, a front link, the lower portion of said front link being pivoted to the front portion of said seat, the upper end portion of said front link being pivoted to the upper portion of said connecting link, said seat, said front link, said connecting link and the stationary portion of the support between the pivotal connections of the connecting link with the support and of the seat with the support forming the links of a four-bar link-mechanism, a back-rest, said back-rest being pivoted to said support at a point spaced from and out of coaxial alignment with the pivotal connection of the seat with the support, a top link, the rear end of said top link being pivoted to an intermediate point of said back-rest above the pivotal connection between the back-rest and the support, the front portion of said top link being pivoted to a point of the connecting link spaced from its pivotal connection with the front link, and locking means associated with said seat and said support for locking said seat in a predetermined position.

11. A reclining article of furniture, comprising: a support, a seat pivoted to said support at its rear end portion, a connecting link, the lower portion of said connecting link being pivoted to said support at a point spaced from the pivotal connection between the seat and the support, a front link, the lower portion of said front link being pivoted to the front portion of said seat, the upper end portion of said front link being pivoted to the upper portion of said connecting link, said seat, said front link, said connecting link and the stationary portion of the support between the pivotal connections of the connecting link with the support and of the seat with the support forming the links of a four-bar link-mechanism, a back-rest, said back-rest being pivoted to said support at a point spaced from and out of coaxial alignment with the pivotal connection of the seat with the support, a top link, the rear end of said top link being pivoted to an intermediate point of said back-rest above the pivotal connection between the back-rest and the support, the front portion of said top link being pivoted to a point of the connecting link spaced from its pivotal connection with the front link, a leg-rest swingably mounted on the front portion of the seat, and means for controlling the movements of said leg-rest in dependence on the movements of a movable member of the article.

12. A reclining article of furniture, comprising: a support, a seat pivoted to said support at its rear end portion, a connecting link, the lower portion of said connecting link being pivoted to said support at a point spaced from the pivotal connection between the seat and the support, a front link, the lower portion of said front link being pivoted to the front portion of said seat, the upper end portion of said front link being pivoted to the upper portion of said connecting link, said seat, said front link, said connecting link and the stationary portion of the support

between the pivotal connections of the connecting link with the support and of the seat with the support forming the links of a four-bar link-mechanism, a back-rest, said back-rest being pivoted to said support at a point spaced from and out of coaxial alignment with the pivotal connection of the seat with the support, a top link, the rear end of said top link being pivoted to an intermediate point of said back-rest above the pivotal connection between the back-rest and the support, the front portion of said top link being pivoted to a point of the connecting link spaced from its pivotal connection with the front link, said back-rest having a downward extension projecting beyond its pivotal connection with the support, a leg-rest swingably mounted on the front portion of the seat, and a controlling link, said controlling link being pivoted at one of its ends to said downward extension of the back-rest, and said controlling link being pivoted at its other end to said leg-rest.

13. A reclining article of furniture, comprising: a support, a seat pivoted to said support at its rear end portion, a connecting link, the lower portion of said connecting link being pivoted to said support at a point spaced from the pivotal connection between the seat and the support, a front link, the lower portion of said front link being pivoted to the front portion of said seat, the upper end portion of said front link being pivoted to the upper portion of said connecting link, said seat, said front link, said connecting link and the stationary portion of the support between the pivotal connections of the connecting link with the support and of the seat with the support forming the links of a four-bar link-mechanism, a back-rest, said back-rest being pivoted to said support at a point spaced from and out of coaxial alignment with the pivotal connection of the seat with the support, a top link, the rear end of said top link being pivoted to an intermediate point of said back-rest above the pivotal connection between the back-rest and the support, the front portion of said top link being pivoted to a point of the connecting link spaced from its pivotal connection with the front link, said back-rest having a downward extension projecting beyond its pivotal connection with the support, a leg-rest swingably mounted on the front portion of the seat, a controlling link, said controlling link being pivoted at one

of its ends to said downward extension of the back-rest and at its other end to said leg-rest, and means whereby the effective length of said controlling link may be varied and adjusted.

- 5 14. A reclining article of furniture, comprising: a support, a seat pivoted to said support at its rear end portion, a unit including a pair of connecting links rigidly connected with each other, one of said connecting links being arranged on one side of the article, the other connecting link being arranged on the other side of the article, said unit being swingably mounted at its lower portion on said support at a point spaced from the pivotal connection between the seat and the support, a front link arranged on each side of the article, the lower portion of each front link being pivoted to the front portion of said seat, the upper end portion of each front link being pivoted to the upper portion of said unit, a back-rest, said back-rest being pivoted to said support at a point spaced from and out of coaxial alignment with the pivotal connection of the seat with the support, and a top link arranged on each side of the article, the rear end of each top link being pivoted to an intermediate point of said back-rest above the pivotal connection between the back-rest and the support, and the front portion of each top link being pivoted to a point of said unit spaced from the pivotal connection of the latter with the front link.

- 15 15. In a reclining article of furniture as claimed in claim 14, said unit including a rod, and each of said connecting links being positively connected at its lower portion with said rod.

ANTON LORENZ.
